SHIRT GUSSET PRESSING MACHINE

John Faber, Jr., Haledon, N. J., assignor to The Prosperity Company, Inc., Syracuse, N. Y., a corporation of New York

Application May 19, 1937, Serial No. 143,432

1 Claim. (Cl. 38—12)

For pressing the gusset of a shirt, to wit, the portion of the sleeve between the elbow and cuff, there is provided a machine including what is termed a buck on which the gusset is arranged by the operator in as smooth condition as possible and a depressible head having a heated portion or iron which coacts with the buck to effect the pressing, the iron being usually formed to straddle the buck. Usually, in order to press both gussets of a shirt at one pressing the bucks and irons are duplicated. Incidentally, only one longitudinal half of a gusset at a time is pressed; that is, having arranged a gusset on its buck so that one such half will be pressed the head is caused to descend to press that half and when, the buck being raised, the gusset is arranged for the pressing of its other longitudinal half the head is caused again to descend to press that half. The cuffs, it may be remarked, are pressed in another machine, usually previously. In pressing the gussets the cuffs are placed so as not to be between the bucks and irons of the head; that is, they are placed beyond the actual gusset pressing means relatively to the operator.

As these machines have heretofore been constructed the gussets were very likely to be left wrinkled so that they would be pressed with undesirable creases therein, especially when the machine was designed to press the gussets of both sleeves at once, because the operator was unable manually to maintain the gussets in such state until the head descended as to eliminate wrinkles or undulations in the gussets.

According to this invention I have equipped a gusset-pressing machine with means whereby the sleeve of a shirt may be held at its free or cuff end prior to the descent of the head and at least up to the instant when the head descends and begins its pressing action; with the sleeve thus held the operator, having smoothed the gusset on the buck, can maintain it without wrinkles, as by holding the sleeve forward of where the pressing is done and so stretching the gusset over the buck.

Given a machine of the class referred to, the invention includes a member coactive with a portion of the buck remote from its free or forward end to form therewith a clamp and being movable from and toward the same. Preferably said member is normally urged toward the buck in any way, as by gravity, and there is releasable means in the machine by which it is held retracted. This means may take the form of a latching device and it may act to latch said member to the actual head of the machine, whereby

on releasing said member before the head descends said member will coact with the buck to clamp the sleeve, as at the cuff, so that the operator can effectively remove and hold removed all wrinkles till the head descends to press, and when the pressing is completed and the head rises said member will be elevated with it. The latching device is preferably on the machine, as the head thereof, rather than on said member, and this permits resort to simple means for effecting release of the latching device by the operator's foot so that both hands remain free for manipulating the gusset on the buck. Where the bucks and heads are duplicated the latching devices for both said sleeve-holding members thus provided may be released, as will appear, first one and then the other from a common control element, as a treadle, thus permitting the operator to clamp and adjust first one and then the other gusset.

In the drawings,

Fig. 1 is a side elevation of a standard type of gusset pressing machine, here duplex, equipped with the present improvement;

Fig. 2 is a section on line 2—2, Fig. 1;

Fig. 3 is an isometric view of the latching assembly; and

Fig. 4 is a fragmentary plan, showing one of the sleeve-holding members coacting with the buck to clamp a sleeve at the cuff.

1 denotes the bucks arranged on the table 2 of the frame 3 of the machine, the right-hand end of each buck, as shown in Fig. 1, being here taken as its forward end. The portion 1a of each buck forward of the section line 2—2 forms the rest with which the head member (to be referred to) 35 coacts to press the gusset, and the portion 1b back of said line forms a rest for the free end portion, as the cuff, of the sleeve, being the portion of the buck with which the head member is non-coactive to press. Both portions are usually covered with fabric and the former portion padded. A standard 4 of the frame upstands at the back and on a horizontal shaft 5 therein is pivoted the head member or head 6, usually bifurcated, as shown, and provided with a brace 6a; the head carries 45 the usual pressing irons 7 formed to straddle the respective bucks and steam-heated, as through pipes 8. It is not material how the head is lowered and raised; usually, however, this is effected automatically, as by pneumatic means controlled 50 by the manually operated devices x and y. So much is a sufficient description of a standard duplex gusset pressing machine.

For each buck according to the present invention there is a holding member normally urged,

here by gravity, against the rearward portion $1b$ of the buck and retractive therefrom. In the example this consists of an arm 10 pivoted on the machine, as on shaft 5 , and having a head 11 forked to straddle the buck when said member is allowed to fall from its retracted position above the buck. One of these is arranged on either side of the standard 4 .

Each holding member may be latched in retracted position in any way, but preferably as follows, thus to simplify the construction and obtain certain obvious advantages in reference to the operation of such holding member.

The head of each holding member has an upward standing hook $11a$. A bracket 12 is affixed by bolts 13 to brace $6a$ and to this are secured housings 14 of the latching devices. The latches 15 of these devices are by springs 16 in the housings normally urged to protrude forwardly into the respective arcuate paths of movement of the hooks $11a$, their beveled faces facing downwardly. Their rear ends also protrude from the housings and to these is connected a floating lever 17 . A flexible connection, as a cable 18 , is connected to this lever nearer one latch than the other and, being suitably guided as shown, extends to a treadle 19 pivoted on the frame.

Assume the parts to be in the positions shown in Fig. 1. The operator places the sleeves of the shirt on the bucks with their gussets a and cuffs b respectively on their portions $1a$ and $1b$. The treadle 19 is then depressed sufficiently to cause one latching device, as the near one in Fig. 1, to release the corresponding holding member, which then falls on the cuff to clamp the same. The gusset is then smoothed. The treadle is now pressed further and (the lever 17 now having a

fulcrum on the latch first retracted—to its limit) the other latching device is caused to release the other holding member, which also falls to clamp the corresponding cuff, whereupon the operator smooths the corresponding gusset. Then, using the hands to hold the sleeves at a point forward of the bucks and hence the gussets in their smooth state, the device x is pressed to cause the head member to descend. When the head member descends the latches are cammed back by the hooks $11a$ and thereupon return to dog the hooks and thus cause the holding members to become re-coupled thereto so that when the head member next rises (by actuating the device y) it elevates said holding members with it. Fig. 2 shows one holding member in coactive relation to the corresponding buck, and the other still elevated.

Of course the invention is conceivably applicable to other machines than for the pressing of the gussets of shirts.

Having thus fully described my invention what I claim is:

The combination, with a machine for the purpose described having a pair of bucks on which to lay the respective garment parts to be treated, of members confined by the machine to move respectively in definite paths toward and normally urged into coactive clamping relation with the respective bucks, a pair of latches arranged on the machine and opposing movement of the respective members into coactive clamping relation with the bucks and retractable to release said members, a lever connecting and movable to retract the latches, and means to effect such movement of the lever connected therewith nearer to one latch than the other.

JOHN FABER, JR.
